UNITED STATES PATENT OFFICE

125,452

DESIGN FOR A HANDLE

Warren H. Marsheck, El Monte, and Glenn O.
Doan, San Pedro, Calif.

Application December 10, 1940, Serial No. 97,234

Term of patent 7 years

To all whom it may concern:

Be it known that we, Warren H. Marsheck and Glenn O. Doan, citizens of the United States and residents of the cities of El Monte and San Pedro, respectively, both in the county of Los Angeles and in the State of California, have invented a new, original, and ornamental Design for a Handle, of which the following is a specification, reference being had to the accompanying drawing, forming part thereof.

In the drawing:

We claim:

The ornamental design for a handle, substantially as shown.

WARREN H. MARSHECK.
GLENN O. DOAN.
